UNITED STATES PATENT OFFICE.

BERNARD FREDRICK WELKER, OF SAN MIGUEL, CALIFORNIA.

BOOKBINDING.

SPECIFICATION forming part of Letters Patent No. 686,373, dated November 12, 1901.

Application filed June 26, 1901. Serial No. 66,138. (No model.)

To all whom it may concern:

Be it known that I, BERNARD FREDRICK WELKER, a citizen of the United States, residing at San Miguel, in the county of San Luis Obispo and State of California, have invented 5 a new and useful Bookbinding, of which the following is a specification.

This invention relates to bookbindings; and the objects of the same are to provide simple 10 and effective cord or twine securing-loops situated in converging slots or kerfs, each twine loop being materially shorter when drawn into its seat than at its point of entry, whereby the loop cannot slip out of its in- 15 tended position and is inseparably held in binding relation to the book, to continue the binding cord or twine terminals under leather or other hinge-guards which are connected to the board covers, the said guards being 20 also held by the cord or twine securing-loops and serving as the direct hinge connections for covers, and thereby prevent the bound signatures or leaf-sections from working loose from the back connection of the covers, 25 and to produce a lasting and strong binding which is prevented from having strain concentrated thereon and giving away from the glue or cement and the binding cord or twine.

The invention consists in the construction 30 and arrangement of the several parts, which will be more fully hereinafter described and claimed.

In the drawings, Figure 1 is a perspective view of a portion of a bound book with the 35 back-covers removed and embodying the features of the invention. Fig. 2 is a longitudinal section through the device shown by Fig. 1. Fig. 3 is a rear elevation of the improved binding, showing the fly-leaves open. Fig. 4 40 is a detail perspective view of one of the cord or twine loops, showing the manner of crossing the extremities thereof. Fig. 5 is a trans- 45 verse section of a portion of the bound leaves and one of the covers.

Similar numerals of reference are employed 45 to indicate corresponding parts in the several views.

The numeral 1 designates a series or plu- 50 rality of signatures or leaf-sections which have their folds arranged in close relation. At the front and back of the assembled sig- 55 natures or leaf-sections are double guards 2,

of leather or other suitable material of a strong and durable nature, the end portions of each guard being securely fastened to a fly-leaf 3 55 and a leaf 4, which is pasted against the inside of the back or cover adjacent thereto. The parts as thus arranged are tightly held in close contact and then brought into opera- 60 tive engagement with a saw or similar cutting device to first form an upper slot or kerf 5, which slants downwardly about three-eighths of an inch and into the book one-quarter of an inch. At a suitable and preferred distance below the said upper slot two re- 65 versely-inclined slots 6 and 7 are next produced by the saw or other device, both slots starting from the same point and of the same length and inward extent as the said upper slot. The third slots or kerfs 8 and 9 are the 70 same as the slots 6 and 7, as are also the fourth slots 10 and 11. By the arrangement of the slots as set forth it will be seen that they will be disposed in inwardly-converging pairs 5 and 6, 7 and 8, 9 and 10, and 11 and 12. The 75 lower slot or kerf 12 slants upwardly and is also of the same length and inward extent as the other slots. The length and inward ex- 80 tent of the said slots may be varied at will, according to the size and general demands of the binding, and it is obvious that the num- 85 ber referred to may be increased or decreased. The slots extend into the guards and the leaves 3 and 4, and consequently when the twine is applied, as will be presently set forth, 85 said latter parts of the book are securely bound in with the signatures or leaf-sections. Lengths of cord or twine 13 are preferably employed for forming the securing means for 90 the binding and are arranged in independent 90 securing-loops, as shown by Fig. 4, with the extremities 14 crossing each other and the terminals 15 frayed and flattened and glued or pasted to the adjacent portions of the guards and leaves 4, the said terminals being directed 95 in accordance with the slant of the slots or kerfs from which they exit. To clearly illus- 100 trate the mode of applying the loops, the slots or kerfs, as shown, will be particularly re- 100 ferred to, and the upper or first loop engages the upper slot or kerf 5 and the next one be- 105 low, which is slot or kerf 6, both of the slots having a converging inclination. The next loop engages the slots 7, and which likewise

inwardly converge, the third loop the slots or kerfs 9 and 10, similarly converging, and the fourth loop the slots 11 and 12, also inwardly converging. It will be seen that when 5 the several loops are drawn into the slots which they engage the indrawing and tightening of the loops will cause them to firmly bear against the inner terminals of the slots, and thereby the dimensions of the loops are 10 reduced materially relatively to the primal arrangement thereof for introduction into the slots. After the securing-loops are applied, as shown and set forth, the opposite sides thereof bear against the guards and are parallel with the folds of the latter and of the signatures or leaf-sections, and when the loops are tightened to the full limit and the terminals secured the sides exert a forceful or 15 strong binding pressure on the portions of the 20 guards and leaves and signatures between them.

When the loops have been secured in place, the slots are supplied with a filling 16 of glue, as shown by Fig. 2, and the portions of the 25 backs of the signatures or leaf-sections are forced or hammered inwardly, as at 17, to reduce or contract the throats of said slots, and thereby render it impossible for the portions of the loops engaging the slots to pull or work 30 out. A coating of glue or cement is then applied to the back of the binding as thus produced, and while in moist condition it is inserted in the back connection 18, Fig. 5, of the covers 19, the leaves 4 being pasted or 35 cured against the inner sides of the latter and the binding thus completed. The guards form the hinges for the covers and the hinge strain is removed from the back of the binding, as the latter is immovably held and the covers 40 open forward of the loops. The guards also

prevent the loops from sinking into the first and last signatures or sections of the book and prevent wear on the said sections.

The improved binding will prove an advantage in saving the books embodying the same 45 from loosening and wearing, as well as produce a flexible action for the covers and, above all, provide a strong and durable binding.

Having thus described the invention, what is claimed as new is—

1. The combination of a plurality of signatures having slots cut into the back portions thereof, said slots converging in pairs inwardly toward each other, securing-loops engaging said inwardly-converging pairs of 55 slots, front and back double guards extending full length of the signatures and secured to the latter by said loops, a back secured to the bound portions of the signatures and having attached covers, portions of the guards 60 being secured against the inner sides of the covers and forming hinges for the latter, and fly-leaves attached to said guards and in part to the inner sides of the covers.

2. A plurality of signatures having slots cut 65 into the back portions thereof converging inwardly toward each other in pairs, and securing-loops engaging said inwardly-converging pairs of slots, said loops having portions thereof extending in reverse directions and 70 the ends frayed and secured to an adjacent portion of the binding.

In testimony that I claim the foregoing as my own I have hereto affixed my signature in the presence of two witnesses.

BERNARD FREDRICK WELKER.
